UNITED STATES PATENT OFFICE.

WILLIAM A. G. ASHLEY, OF NEW BEDFORD, MASSACHUSETTS, ASSIGNOR OF TWO-THIRDS TO JAMES M. LAWTON, JR., AND AUSTIN T. HOWLAND, OF SAME PLACE.

KNOB ATTACHMENT.

SPECIFICATION forming part of Letters Patent No. 485,145, dated October 25, 1892.

Application filed June 22, 1892. Serial No. 437,551. (No model.)

To all whom it may concern:

Be it known that I, WILLIAM A. G. ASHLEY, a citizen of the United States, residing at New Bedford, in the county of Bristol and State of Massachusetts, have invented certain new and useful Improvements in Door-Knob Attachments, of which the following is a specification, reference being had to the drawings hereunto annexed.

10 My invention relates to door-knob attachments; and it has for its object to provide a device by means of which knobs may be adjusted to doors of different thickness, and also any lost motion occasioned by the wear 15 of the knob-shank against the rose may be taken up.

The accompanying drawings illustrate my invention, in which—

Figure 1 is a view of the edge of a door 20 having knobs attached and supplied with my invention. Fig. 2 is a view showing the knob, knob-shank, rose, and the escutcheon in longitudinal section, and showing the different parts of my invention properly assembled. Fig. 3 is a plan view of the door-escutcheon. Fig. 4 is a plan view of my invention, showing the knob-spindle in cross-section.

Similar letters refer to similar parts in the 30 several views.

a represents the edge of a door, having knobs attached, one of which *b* is provided with the ordinary rose. The knob *w* is provided with my device for adjustment.

35 *c* is the rose, consisting of the plate *r*, having the screw-threaded opening *h* and the hub *e*, of a size to loosely embrace the knob-shank *q*.

f is a sleeve loosely embracing the knob- 40 spindle *k* and externally screw-threaded to fit the screw-threaded opening *h* and provided with the open-ended slot *g* and the head *m*, fitting within the hub *e*.

45 *d* is an escutcheon-plate having the opening *l* of a size to loosely admit the screw-threaded sleeve *f* and provided with the projection *i*, adapted to fit in the open-ended

slot *g* and prevent said sleeve from turning and at the same time admit of its lateral movement. The escutcheon *d* is further provided with the slots *n*.

The operation of my device is as follows: The ordinary holes are bored in the door, and the escutcheon *d* secured in place. The knob *b*, with the knob-spindle *k*, is then inserted. The rose *c*, having the sleeve *f* screwed down to its limit, is then slipped over the knob-spindle, with the slot *g* embracing the projection *i*. The knob *w* is then secured on the end of the knob-spindle, and if 55 there be any lateral motion of the spindle in the door it is taken up by turning the rose *c* to the right. This motion causes the sleeve *f* to be drawn outward and its head *m* to press against the knob-shank *q* until 60 all the lateral motion of the knob-spindle is taken up. In turning the knob *w* it will be observed that the friction occurs between the head *m* of the sleeve *f* and the face of the knob-shank *q*, and that the knob-shank 70 *q* fits loosely in the hub *e* of the rose, so that in turning the knob *w* there is no tendency to turn the rose *c* at the same time; but to guard against the accidental turning of the rose *c* by the hand I provide it with the 75 screw-holes *o*, which coincide with the slots *n* in the escutcheon, through which holes and slots I put the screws *s* and screw them into the wood of the door.

When, from wear, there is lateral motion 80 of the knob-spindle, it is taken up by removing the screws *s* and giving the rose *c* a quarter-turn or more to the right, when the screws are again adjusted. The device will operate satisfactorily without means for 85 curing the rose *c* from turning; but in some instances it may be deemed advisable to employ such means.

Having thus described my invention, what I claim, and desire to secure by Letters Patent, is—

In a knob attachment of the character described, an internally-screw-threaded rose having a hub adapted to loosely embrace the

knob-shank, and an externally-screw-threaded sleeve fitting in said rose, having its inner end provided with an open-ended slot, in combination with an escutcheon having an opening adapted to loosely receive the screw-threaded sleeve and provided with an inwardly-projecting lug adapted to fit in the

open-ended slot in the sleeve, substantially as shown and described.

WILLIAM A. G. ASHLEY.
